UNITED STATES PATENT OFFICE.

ROBERT MARSHALL, OF HAMILTON, ONTARIO, CANADA.

CRIMPING-MACHINE.

SPECIFICATION forming part of Letters Patent No. 406,175, dated July 2, 1889.

Application filed October 26, 1888. Serial No. 289,223. (No model.)

To all whom it may concern:

Be it known that I, ROBERT MARSHALL, a citizen of Canada, residing at Hamilton, in the county of Wentworth, Province of Ontario, Canada, have invented a new and useful 5 Machine for Crimping the Leather Uppers for Boots and Shoes, of which the following is a specification.

My invention relates to improvements in 10 crimping-machines in which double sliding molds provided with springs of the same shape slide horizontally on the top of a double mold which is secured rigid to the frame of the machine. These sliding molds are 15 operated upon by the mechanism of the machine until the center of each mold arrives at the center of the double mold, and remains there while a trix, hereinafter described, performs a full stroke, carrying a piece of leather 20 (that was placed between the spring and sliding mold) through the molds, and while passing through it engages with a matrix, which forms and crimps the leather into a seamless upper.

25 The objects of my improvements are, first, to provide a machine having its important parts working automatically, so as to insure speed in crimping; second, to afford facilities for the placing of the leather while the machine is engaged with and crimping another; 30 third, to provide an automatic device to release the crimp from the trix when at the end of its stroke. I attain these objects by the mechanism illustrated in the accompanying 35 drawings, in which—

Figure 1 is a side elevation of an entire machine with its bevel-wheels in section, the drive-pulley denoted by its rim-circle line, the matrix bolted to its rod with broken lines, 40 and the trix, which is the same in shape to the press-plates and between them, is hid from view. Fig. 2 is a front sectional elevation through the broken line xx and at right angles with the same, the upper part of front legs and the hind part of bed-plate and machine broken away.

Similar letters refer to similar parts throughout the several views.

In the drawings, the metal frame a , its legs 50 or standards a' and a'' , front legs' brace a^2 , bed-plate a^4 , hind supporting-bracket a^5 , large spur-wheel shaft-bearing a^6 , and the

large bevel-wheel shaft-bearing a^7 , with its upper part a , constitute the metal frame-work of the machine.

55 B B are the drive-pulleys (fast and loose) of the entire machine. The bracket B' , which supports the same, (and shown broken in Fig. 2,) is bolted on a convenient place to the frame a of the machine.

60 B^2 is a belt-shifter attached to a foot-lever B^3 by means of lever B^4 , with fulcrum B^5 .

When crimping leather with the machine, a flat piece of leather (oval in shape) is placed 65 on the center of the double sliding mold c' and under the springs c , both of which are attached together and slide horizontally to and fro attached to a slide in the rigid V -groove c^2 , and also on the rigid bar c^3 on the opposite side of molds. The distance 70 between the double sliding molds and also the double rigid mold is just sufficient to allow the trix with leather to pass through. These sliding molds are operated and moved horizontally by means of the levers D , connected 75 to the said molds and to the double screw-shaft by means of nuts D^2 , which traverse the said shaft, each nut having a connecting-rod D^3 connected to long levers D , with their fulcrums on the front legs A' .

A rigid guide 80 d is bolted to the said legs A' near their top, to facilitate the steady and easy reciprocating motion of the said molds. The trix E , which consists of an angular former corresponding 85 in shape with the matrix, and which is bolted to the lower end of its rod E^2 , is brought down upon the leather by means of a stud E^3 in bevel-wheel E^3 , thus forming a crank working into the longitudinal slotted bar E^4 . This mechanism gives the trix its motion up and 90 down. At the time the trix is coming down the double press-plates J also come down in the guides J^4 , their rods J' having studs J^2 , which lie in a cam-race J^3 , formed on the back 95 of the bevel-wheel E^3 , which is revolved by the miter-gear S^2 , meshing with teeth on the back of bevel-wheel E^3 . Thus the trix and press-plates are reciprocated together, 100 though by different motions, the said cam allowing the press-plates to fall lightly on the springs c , and when the trix is passing through the molds it draws the said leather from underneath the springs and engages with the matrix I in close proximity to the corrugated

metal plates H. Each plate is backed by a thickness of rubber for the purpose of allowing for the varying thicknesses of leather coming down with the trix and pressing with the said plates close to the leather, giving the same an even surface. Before the trix is through the rigid molds F the rubber rollers R engage with the leather crimp, one on each side of the crimp, just before leaving the mold F, and are for the purpose of smoothing and finishing the same. The matrix I, the upper part of which is shaped the same as the lower part of the trix, forms and shapes the crimp against the trix. The matrix-rod I', bolted to the same, (shown by broken lines in Fig. 1,) is reciprocated in the grooved guides I² I² by means of the crank K on the lower end of bevel-wheel shaft in bearing a⁷, transmitting motion to the large spur-wheel shaft in bearing a⁶. The pin of said crank is attached to the said spur-wheel and also between the wheel and pin end of crank. The pin works in the longitudinal guide-bars L, the lower bar of which forms the upper cross-bar for the matrix-rod I'. At the ends of these bars L, and perpendicular with them is a bolt which passes through both bars, with a coil-spring S' around each and resting on the upper longitudinal bar L, which forms the lower cross-bar for the upper end of matrix-rod I'. These springs give and allow tension to the matrix when engaged. The upper end of said rod reciprocates through the upper part of frame a. The lower part, also with the two press-plate rods J', reciprocate through the said frame a. The two supports m m and their surface-plates n n for under side pressure, for the purpose of taking the leather crimp off the trix when through molds F F, are operated by the double screw-shaft O. The fulcrums S S of said arms are on the lower end of the guide-bar I².

The rubber rollers R R before mentioned revolve in the bearings R' R', each roller having a small spur-wheel T keyed on the lower end of its shaft, each revolving in an opposite direction to the trix when coming down, and the driver of said wheels is a third spur-wheel T' on the upper end of shaft U, and at the lower end of said shaft is a pulley U', driven by belt from the larger pulley V on the lower end of shaft V' in bracket-bearings V², which are bolted to the frame a.

It will be readily perceived by the drawings how motion is transmitted from one part of the machine to another. The first pinion bevel-wheel S² and driver of the whole machine is keyed onto the end of the shaft of the two drive-belt pulleys B B. The said bevel-wheel S² drives the bevel-wheel E³, with

cam on its face working in bearing a⁷, thus turning the crank K, the latter turning the spur-wheel a⁸ in bearing a⁶, thus giving motion to the small spur-wheel V⁴, keyed to the upper end of shaft V', thence to the other component parts of the machine, as before described.

The present invention is an improvement upon the United States Letters Patent granted me the 24th day of August, 1886, No. 348,145, and I make no claim in this application to anything shown in the said patent.

Having thus described my device and its advantages, what I claim as my invention, and desire to secure by Letters Patent, is—

1. The combination of the frame a of the machine, the trix with its rod and longitudinal slotted bar E⁴, bevel-wheel E³, with its cam J³, with and for reciprocating the double press-plates J, substantially as described.

2. The combination of the sliding molds c', grooved bearings c², secured to the rigid mold of the machine, the guide-bar c³, springs c, the double screw-shaft D', nuts D², levers D, angle-shaft D³, with its wheels keyed onto the same, and all driven by the mechanism, substantially as herein described.

3. The combination, with the frame of the machine, of the rubber rollers and bearings, spur-wheels T and T', shaft U, with its pulley U', the large pulley V on shaft V', driven by the mechanism of the machine, as described.

4. The combination, with the frame of the machine, of the matrix I, with its rod I', the longitudinal cross-bars L, spiral springs S', the crank K, and the guide-bars I², substantially driven as herein described.

5. The combination of the under side-pressure surface-plates N N, their arms M M, the double-screwed movement-shaft O, and the trix E, with its rod E', and the bevel-wheel E³, all driven by the mechanism of the machine, as described.

6. The combination of the trix E, with its rod E', the sliding molds c', with their springs C, the rigid molds F, bolted to the frame a and provided with the corrugated-metal plates H H, with rubber backings, the matrix I and its rod I', the double press-plates J, with rods J', and the under-pressure surface-plates, all driven by the mechanism, as herein described and set forth.

Dated at Hamilton, this 5th day of March, A. D. 1888.

ROBERT MARSHALL.
